UNITED STATES PATENT OFFICE.

AUGUST S. HELD, OF FREEPORT, ILLINOIS.

COMBINED MOP AND SCRUB-BRUSH.

SPECIFICATION forming part of Letters Patent No. 732,744, dated July 7, 1903.

Application filed October 10, 1902. Serial No. 126,684. (No model.)

To all whom it may concern:

Be it known that I, AUGUST S. HELD, a citizen of the United States of America, residing at Freeport, in the county of Stephenson and 5 State of Illinois, have invented certain new and useful Improvements in a Combined Mop and Scrub-Brush, of which the following is a specification.

This invention has for its object the production of combined mops and scrub-brushes, so contrived and arranged that they may be used both in such combination and separately; and it consists of certain new and useful features of construction and combinations of parts especially devised to those ends, all as hereinafter fully described, and specifically pointed out in the claims.

Referring to the accompanying drawings, which form a part of this specification, Figure 1 is a top plan view of a combined mop and scrub-brush embodying my invention and adapted to be used for both mopping and scrubbing. Fig. 2 is a section at the dotted line 2 2 in Fig. 1 of parts there shown. Fig. 3 is a like section, also at such dotted line 2 2 in Fig. 1, showing the movable jaw of the mop-head thrown away from its fixed jaw by means of its controlling - lever in order that the brush-attaching plate thereof, with its brush, 30 may be detached therefrom. Fig. 4 is an isometrical detail of the brush-attaching plate. Figs. 5, 6, and 7 are views showing a modified form of one of the elements (indicated by the letter B³) composing the utensil illustrated in the foregoing views.

Like letters of reference indicate corresponding parts throughout the several views.

A is a mop-handle.

B is a fixed clamping-jaw provided with a handle-socket B' and having a channel B², extending along lengthwise of the lower and straight edge thereof, and attaching-flanges B³, projecting laterally therefrom.

C is a brush-attaching plate, having hooks 45 C' on one edge thereof, adapted to engage with either edge of the channel B² in the fixed jaw B, and provided with an upwardly-extending resilient member C², having depressions C³ therein, adapted to engage with and be disengaged from the attaching-flanges B³ on the

fixed clamping-jaw B by virtue of its resiliency.

D is a scrub-brush, secured by means of screws D' to the brush-attaching plate C.

E is a movable clamping-jaw parallel with 55 the fixed jaw B, having its ends E' extending and converging rearwardly and united by connecting means to be described hereinafter.

F is a ring encircling and slidable on the handle A.

G is a bifurcated lever mounted by the free ends G' of its furcations on pivot-bearings G² on the ring F and having openings G³ therethrough to admit and pivotally connect with the ends E' of the movable jaw E.

H is a coiled spring encircling the handle A, compressible between the fixed clamping-jaw B and slidable ring F and normally acting to force the movable jaw E toward the fixed jaw B.

I is a mop inserted between the jaws B and E.

A pintle J may be inserted through the handle A or an equivalent device be attached to such handle in place of the flanges B³ on the fixed clamping-jaw B without departing 75 from the spirit and scope of my invention.

By pressing the thumbs upon the member C² at C⁴ of the attaching-plate C the latter may be disengaged first from the flanges B³ on the fixed jaw B and then from the channel 80 B² therein, thus leaving the mop and brush to be used separately, if desired.

What I claim as new, and desire to secure by Letters Patent, is—

1. In a utensil of the class described, in 85 combination, a fixed clamping-jaw, having a channel extending along lengthwise of the lower and straight edge thereof, attaching means located above said jaw, a brush-attaching plate having hooks, on one edge thereof, adapted to engage with either edge of the channel in the fixed jaw, and provided with an upwardly-extending resilient member having depressions therein adapted to engage with and be disengaged from the attaching 95 means, by virtue of its resiliency, and a scrub-brush fast to the brush-attaching plate, substantially as and for the purpose specified.

2. In a utensil of the class described, in 100 combination, a fixed clamping-jaw, having a

channel extending along lengthwise of the lower and straight edge thereof and attaching-flanges projecting laterally therefrom, a brush-attaching plate having hooks, on one edge thereof, adapted to engage with either edge of the channel in the fixed jaw, and provided with an upwardly-extending resilient member having depressions therein adapted to engage with and be disengaged from the attaching-flanges, on the fixed clamping-jaw,

by virtue of its resiliency, and a scrub-brush fast to the brush-attaching plate, substantially as and for the purpose specified.

In testimony whereof I have signed my name to this specification in the presence of 15 two subscribing witnesses.

AUGUST S. HELD.

Witnesses:

JOHN M. IRWIN,
W. H. J. STRATTON.
